United States Patent Office

Des. 214,108
Patented May 6, 1969

214,108

DISPLAY CABINET FOR EYEGLASS FRAMES OR THE LIKE

Rolf Sulzberger, 3 Cedar St.,
Worcester, Mass. 01609

Filed Mar. 14, 1968, Ser. No. 10,967

Term of patent 14 years

Int. Cl. D6—01

U.S. Cl. D80—11

FIG. 1

FIG. 2

FIG. 3

FIGURE 1 is a front perspective view of a display cabinet for eyeglass frames or the like showing my new design;

FIG. 2 is a side elevational view thereof; and

FIG. 3 is a front elevational view thereof showing two display panels in an open position.

The broken line representation of a mirror in FIGURE 1 is for purposes of illustration only.

I claim:

The ornamental design for a display cabinet for eyeglass frames or the like, substantially as shown and described.
